DESIGN FOR A FRAME FOR MIRRORS OR THE LIKE

Leo Marder, Brooklyn, N. Y.

Application October 11, 1938, Serial No. 80,365

Term of patent 3½ years

To all whom it may concern:

Be it known that I, Leo Marder, a citizen of the United States and a resident of Brooklyn, in the county of Kings and State of New York, have invented a new, original, and ornamental Design for a Frame for Mirrors or the like, as shown, of which the following is a specification, reference being had to the accompanying drawing, forming a part thereof.

Figure 1 is a front face view showing my design for a frame for mirrors or the like;

Figure 2 is a back view of the same;

Figure 3 is an edge view of the same;

Figure 4 is a magnified section taken on the line 4—4 of Figure 1;

Figure 5 is a magnified section taken on the line 5—5 of Figure 1;

Figure 6 is a magnified section taken on the line 6—6 of Figure 1.

The design is also adapted for use as a frame for brushes.

I claim:

The ornamental design for a frame for mirrors or the like, substantially as shown and described.

LEO MARDER.
